ELECTRIC CONSUMPTION**

BACKGROUND OF THE INVENTION

1. Field of the Invention

The invention relates to a color display plasma display panel (hereinafter, referred to as PDP) as a self light emitting type flat display using a gas discharge.

2. Description of Related Art

In recent years, in accordance with the increase in size of a display apparatus, a demand for thin display apparatuses is growing and various thin display apparatuses have been put into practical use. AC (alternate current discharge) type PDP is drawing attention in this field as one of the thin display apparatuses.

In an AC type PDP, a plurality of sets of row electrode pairs corresponding to "rows" of a screen are provided on one of two glass substrates which face each other and a plurality of column electrodes corresponding to "columns" are provided on the other glass substrate. Further, a mixture of rare gases containing mainly neon, xenon, and the like is sealed between both of the glass substrates. A discharge cell corresponding to one pixel is formed in each crossing portion of the row electrodes and the column electrodes.

To allow the PDP to execute a light emission display, a voltage is applied across the pair of row electrodes and only the discharge cells corresponding to an input video signal among the discharge cells formed in the crossing portions are allowed to perform a discharge light emission, thereby obtaining a display image corresponding to the input video signal. In this structure, a current flows between the electrodes in accordance with the applied voltage, and electric power is consumed by the resistance which the electrodes have.

**OBJECTS AND SUMMARY OF THE
INVENTION**

It is an object of the invention to provide a plasma display panel which can reduce an electric power consumption.

According to the first aspect of the invention, there is provided a plasma display panel comprising: a front glass substrate serving as a display screen; a plurality of row electrodes arranged in parallel on the inner surface of the front glass substrate; a back glass substrate; a plurality of column electrodes arranged on the inner surface of the back glass substrate so as to be extended in the direction which crosses the row electrodes; and a discharge space which is formed between the front glass substrate and the back glass substrate and in which a discharge gas is sealed, wherein each of the row electrodes is constituted by a transparent electrode for performing a discharge and a bus electrode for supplying a voltage to the transparent electrode, and an area of each of the transparent electrodes gradually decreases from a center portion of the display screen to the peripheral portion thereof.

According to the second aspect of the invention, there is provided a plasma display panel comprising: a front glass substrate serving as a display screen; a plurality of row electrodes arranged in parallel on the inner surface of the front glass substrate; a back glass substrate; a plurality of column electrodes arranged on the inner surface of the back glass substrate so as to be extended in the direction which crosses the row electrodes; and a discharge space which is formed between the front glass substrate and the back glass

substrate and in which a discharge gas is sealed, wherein each of the row electrodes is constituted by a transparent electrode for performing a discharge and a bus electrode for supplying a voltage to the transparent electrode, the display screen is divided into a plurality of regions, and an average area of the transparent electrodes existing in each of the regions gradually decreases from a center region of the display screen to the peripheral region thereof.

BRIEF DESCRIPTION OF THE DRAWINGS

10 FIG. 1 is a diagram showing a schematic construction of an AC type PDP;

FIG. 2 is a diagram showing the structure of each of adjacently formed blue discharge cell, green discharge cell, and red discharge cell which are extracted for the purpose of illustration from the PDP shown in FIG. 1;

15 FIG. 3 is a diagram for explaining a correspondence between regions in the display screen of the PDP and an area of a transparent electrode in the discharge cell existing in each region;

20 FIG. 4 is a diagram showing an example of an area of the transparent electrode in each of the four discharge cells existing in each of regions E₁ to E₃ of the PDP shown in FIG. 3 and an average area of the transparent electrodes in each region;

25 FIG. 5 is a diagram showing another structure of each of the blue discharge cell, green discharge cell, and red discharge cell;

30 FIG. 6 is a diagram showing still another structure of each of the blue discharge cell, green discharge cell, and red discharge cell; and

35 FIG. 7 is a diagram showing further another structure of each of the blue discharge cell, green discharge cell, and red discharge cell.

**DETAILED DESCRIPTION OF THE
PREFERRED EMBODIMENTS**

FIG. 1 is a diagram showing a schematic construction of an AC type PDP.

40 In FIG. 1, n row electrodes X₁ to X_n and row electrodes Y₁ to Y_n are alternately arranged in parallel on an inner surface (surface which faces a back glass substrate 113, which will be explained later) of a front glass substrate 110 serving as an image display surface, respectively. In this structure, one row of the screen of the PDP is formed by a pair of row electrodes X and Y.

45 The row electrodes X₁ to X_n and row electrodes Y₁ to Y_n are covered by a dielectric material layer 111 on which a protecting layer 112 made of magnesium oxide or the like has been deposited by an evaporation deposition method. A discharge space 114 is provided in which a mixture of rare gases containing mainly neon, xenon, and the like is sealed as a discharge gas. The discharge space 114 is formed between the dielectric material layer 111 and the back glass substrate 113. Column electrodes D₁ to D_m are formed on an inner surface (surface which faces the front glass substrate 110) of the back glass substrate 113 so as to be extended in the direction which crosses the row electrodes X₁ to X_n and row electrodes Y₁ to Y_n. The column electrodes D₁ to D_m are separated by a barrier 115 as shown in FIG. 1. Further, a fluorescent material layer 116 for performing a blue light emission, a green light emission, or a red light emission is formed so as to cover each column electrode D and the wall surfaces of the barrier 115.

50 55 60 65 65 A discharge cell corresponding to one pixel is formed in each of crossing portions of the column electrode D and the row electrodes X and Y.

That is, the blue discharge cells are formed in the crossing portions of the column electrode D and the row electrodes X and Y where the fluorescent material layer 116 for performing the blue light emission has been formed. The green discharge cells are formed in the crossing portions of the column electrode D and the row electrodes X and Y where the fluorescent material layer 116 for performing the green light emission has been formed. Further, the red discharge cells are formed in the crossing portions of the column electrode D and the row electrodes X and Y where the fluorescent material layer 116 for performing the red light emission has been formed.

FIG. 2 is a diagram showing only three discharge cells comprising a blue discharge cell, a green discharge cell, and a red discharge cell which are adjacently formed, in which these cells are extracted from the PDP shown in FIG. 1 and shown. FIG. 2 is a diagram when it is seen from the display surface side of the front glass substrate 110 in the PDP shown in FIG. 1.

As shown in FIG. 2, a T-shaped transparent electrode X_{TR} is formed on each of a blue discharge cell C_B , a green discharge cell C_G , and a red discharge cell C_R . Each of the transparent electrodes X_{TR} is connected to one bus electrode X_{BUS} . The row electrode X corresponding to one row is formed by the bus electrode X_{BUS} and the plurality of transparent electrodes X_{TR} connected thereto. A transparent T-shaped transparent electrode Y_{TR} is formed on each of the blue discharge cell C_B , green discharge cell C_G , and red discharge cell C_R . Each of the transparent electrodes Y_{TR} is connected to one bus electrode Y_{BUS} . The row electrode Y corresponding to one row is formed by the bus electrode Y_{BUS} and the plurality of transparent electrodes Y_{TR} connected thereto. Each of the pair of transparent electrodes Y_{TR} and X_{TR} comprises a narrow width portion a and a wide width portion b which are extended along the barrier 115. One end of the narrow width portion a of each of the transparent electrodes Y_{TR} and X_{TR} is electrically connected to each bus electrode (Y_{BUS} , X_{BUS}). The wide width portions b of the transparent electrodes Y_{TR} and X_{TR} are formed at positions which are away from each other by a predetermined distance G. This space becomes a discharge gap. That is, when a voltage is applied across the bus electrodes Y_{BUS} and X_{BUS} , this voltage is supplied to the transparent electrodes Y_{TR} and X_{TR} and a discharge is generated in the discharge gap.

The blue discharge cell C_B , green discharge cell C_G , and red discharge cell C_R having the row electrodes X and Y having the electrode form as shown in FIG. 2 are arranged in a matrix shape in the PDP.

In the PDP according to the invention, the areas of the transparent electrodes Y_{TR} and X_{TR} formed in each discharge cell gradually decrease from the center portion of the display screen to the peripheral portion thereof.

That is, the area of each of the transparent electrodes Y_{TR} and X_{TR} gradually decreases from that existing in a center region E_1 of the display screen of the PDP to those existing in regions E_2 , E_3 , ..., and E_P as shown in FIG. 3. As a method of decreasing the areas of the transparent electrodes Y_{TR} and X_{TR} , for example, an electrode width W_1 in the narrow width portion a, an electrode width W_2 in the wide width portion b, and the discharge gap G shown in FIG. 2 are set to fixed widths, respectively, and an electrode length L_2 in the wide width portion b is set to be short while an electrode length L_1 in the narrow width portion a is set to be long.

By sequentially reducing the areas of the transparent electrodes Y_{TR} and X_{TR} which are formed in the discharge

cell existing in the peripheral region of the screen as the region approaches the periphery as mentioned above, the electric power consumption is also reduced by an amount corresponding to the reduced amount of the areas of the transparent electrodes as resistors. Although the luminance in the screen peripheral portion is reduced by an amount corresponding to the reduced areas of the transparent electrodes Y_{TR} and X_{TR} as compared with that in the center portion of the screen, a display image in the peripheral portion of the screen is not so significant on the sense of sight.

According to the invention, therefore, the electric power consumption can be reduced without deteriorating the picture quality.

If a luminance change ratio according to an area change of the transparent electrodes as mentioned above is larger than a display gradation due to an influence by a variation or the like of processing precision at the time of formation of the transparent electrodes Y_{TR} and X_{TR} , there is a possibility of occurrence of a luminance variation.

An average area of the transparent electrodes Y_{TR} and X_{TR} in each of the regions E_1 to E_P as shown in FIG. 3, therefore, gradually decreases from the region E_1 in the center portion of the screen toward the region E_P in the peripheral portion of the screen.

For example, as shown in FIG. 4, when four discharge cells comprising the first to fourth discharge cells exist in the regions E_1 to E_3 , an area of the transparent electrodes of the first discharge cell existing in the region E_1 is assumed to be "10", an area of the transparent electrodes of the second discharge cell is assumed to be "10", an area of the transparent electrodes of the third discharge cell is assumed to be "9", and an area of the transparent electrodes of the fourth discharge cell is assumed to be "11". The average area of the transparent electrodes in the region E_1 is, consequently, equal to "10". An area of the transparent electrodes of the first discharge cell existing in the region E_2 is assumed to be "9", an area of the transparent electrodes of the second discharge cell existing is assumed to be "8", an area of the transparent electrodes of the third discharge cell existing is assumed to be "9", and an area of the transparent electrodes of the fourth discharge cell existing is assumed to be "10". The average area of the transparent electrodes in the region E_2 is, consequently, equal to "9". An area of the transparent electrodes in the first discharge cell existing in the region E_3 is assumed to be "9", an area of the transparent electrodes in the second discharge cell existing is assumed to be "7", an area of the transparent electrodes in the third discharge cell existing is assumed to be "8", and an area of the transparent electrodes in the fourth discharge cell existing is assumed to be "8". The average area of the transparent electrodes in the region E_3 is, consequently, equal to "8".

As mentioned above, in the embodiment shown in FIG. 4, the average area of the transparent electrodes existing in the region sequentially decreases to "10", "9", and "8" from the center region E_1 of the screen toward the region E_3 . As shown in FIG. 4, the third discharge cell having the transparent electrodes whose area is equal to "9" as an average area of the transparent electrodes in the adjacent region E_2 exists in the region E_1 in which the average area of the transparent electrodes is equal to "10". That is, the transparent electrodes having the same area are included in each of the adjacent regions.

In accordance with this construction, therefore, even if there is a variation or the like of the processing precision at the time of formation of the transparent electrodes, since the

luminance change ratio according to the area change of the transparent electrodes as mentioned above is smaller than the display gradation, the luminance variation as mentioned above can be prevented.

In the embodiment shown in FIG. 2, although the T-shaped transparent electrodes Y_{TR} and X_{TR} are individually formed in each discharge cell, it is also possible to use a structure as shown in FIG. 5 in which the wide width portions b of the adjacent transparent electrodes Y_{TR} and X_{TR} formed every discharge cell are coupled. 10

In place of the T-shaped transparent electrodes Y_{TR} and X_{TR} as shown in FIG. 2, rectangular transparent electrodes Y_{TR} and X_{TR} as shown in FIG. 6 can be also used. In brief, it is sufficient that independent island-shaped transparent electrodes are formed every discharge cell. 15

Further, as shown in FIG. 7, the barrier 115 can be also formed in parallel crosses so as to surround transparent electrodes Y_{TR} and X_{TR} formed in each discharge cell.

As described in detail above, in the plasma display panel according to the invention, since the areas of the transparent electrodes for discharging gradually decrease from the center portion of the display screen toward the peripheral portion thereof, the electric power consumption can be reduced without deteriorating the picture quality on the 25 sense of sight.

What is claimed is:

1. A plasma display panel comprising:
a front glass substrate serving as a display screen;
a plurality of row electrodes arranged in parallel on an 30 inner surface of said front glass substrate;
a back glass substrate;
a plurality of column electrodes arranged on an inner surface of said back glass substrate so as to be extended in the direction which crosses said row electrodes; and
a discharge space which is formed between said front glass substrate and said back glass substrate and in which a discharge gas is sealed, 35
wherein each of said row electrodes is constituted by a 40 transparent electrode for performing a discharge and a bus electrode for supplying a voltage to said transparent electrode, and

an area of each of said transparent electrodes gradually decreases from a center portion of said display screen to a peripheral portion thereof.

2. A panel according to claim 1, wherein
a discharge cell corresponding to one pixel is formed in each crossing portion of said row electrodes and said column electrodes, and
said transparent electrodes are a plurality of island-shaped transparent electrodes independently formed every said discharge cell.
3. A panel according to claim 2, wherein said island-shape is a T-shape.
4. A plasma display panel comprising:
a front glass substrate serving as a display screen;
a plurality of row electrodes arranged in parallel on an inner surface of said front glass substrate;
a back glass substrate;
a plurality of column electrodes arranged on an inner surface of said back glass substrate so as to be extended in the direction which crosses said row electrodes; and
a discharge space which is formed between said front glass substrate and said back glass substrate and in which a discharge gas is sealed,
wherein each of said row electrodes is constituted by a transparent electrode for performing a discharge and a bus electrode for supplying a voltage to said transparent electrode, and
said display screen is divided into a plurality of regions, and an average area of said transparent electrodes existing in each of said regions gradually decreases from a center region of said display screen to a peripheral region thereof.
5. A panel according to claim 4, wherein
a discharge cell corresponding to one pixel is formed in each crossing portion of said row electrodes and said column electrodes, and
said transparent electrodes are a plurality of island-shaped transparent electrodes independently formed every said discharge cell.
6. A panel according to claim 5, wherein said island-shape is a T-shape.
